UNITED STATES PATENT OFFICE.

GEORGE B. HURD, OF NEW YORK, N. Y.

DESIGN FOR A BOX.

SPECIFICATION forming part of Design No. 25,437, dated April 28, 1896.

Application filed January 23, 1896. Serial No. 576,603. Term of patent 31 years.

To all whom it may concern:

Be it known that I, GEORGE B. HURD, a citizen of the United States, residing at New York, in the county and State of New York, 5 have invented and produced a new and original Design for Stationery-Boxes, of which the following is a full, clear, and exact specification.

My design consists of a box having the compartments *a*, *b*, and *c*. The compartment *a* is formed by the vertical walls *d e*. The lines of the end pieces *ff* extend downwardly at an angle from the upper edge of pieces *f* to the points *g*, respectively, and are thence continued in parallel lines with each other to the bottom of the box. The walls *h* are vertical and arranged parallel with the walls *d e*, forming with the end pieces *ff* the compartments *i j*. The walls *k* of the lids are arranged to 15 be, when closed, at right angles with the lines

ff. The end pieces *l* of said lids are triangularly shaped over all their lines, when closed being parallel with the line *f*, the opposite line *m* then being a vertical continuation of the vertical line of wall *h*. The hypotenuse 25 line of end pieces *l* is arranged to be at right angles to the oblong-shaped flap-piece or wall *k*. Semicircularly-shaped recesses *o* are formed in the upper edges of the walls *d e*.

What I claim is—

The design for a box, substantially as shown and described.

In testimony that I claim the foregoing I have hereunto set my hand this 23d day of December, 1895.

GEORGE B. HURD.
